UNITED STATES PATENT OFFICE

JACOB A. L. MÖLLER, OF NEW YORK, N. Y.

EQUALIZER ROD

Application filed February 21, 1925. Serial No. 10,940.

The present invention relates to paper or fabric coating machinery, and more particularly to improvements in equalizer devices adapted to be employed in the coating of carbon or other transfer sheets.

In the ordinary carbon paper coating machinery a revolving equalizer rod or scraper is generally employed for removing the excess of pigment or coating on the paper 10 which is applied to the paper during the coating process.

Equalizer rods of the form in use at the present time are rapidly worn out and consequently have to be frequently replaced by 15 new rods. The rods of the form generally used are made by winding a round steel wire of the proper diameter around a small steel rod or bar so that the windings thereon are in the form of a helix and provide a continuous 20 helical groove between the adjacent strands of the wire which is closely wound thereon. By forming the equalizer rod in this manner a uniform depth of groove occurs on all portions of the rod, and a particular 25 rod is adaptable for and may be adjusted substantially only for one depth of coating.

One of the main difficulties which has been encountered in the use of a revolving equalizer rod of the form above described which is 30 generally employed in coating machinery is the rapid wear of the rod because of contact, both with its supporting trough and with the paper and dope or coating material applied thereto. The wear on the rod causes more 35 or less change in the amount of coating which will be applied to the paper sheet and finally the wire or thread on the equalizer rod breaks, thus necessitating replacement of the rod.

It is the primary object of the present invention to provide an improved form of equalizer rod which may be manufactured at a moderate cost and which will have a 40 much longer life than any form heretofore devised.

Another object of the invention is to provide an equalizer rod of such a form that as 45 wear occurs thereon no replacement may be necessary, as is caused for example, by the breaking of the wire on the ordinary equalizer rod. In the form of rod which I have

devised the rod may be slightly turned in position after a considerable wear has occurred on one part of the rod and by this means the same depth of coating may be attained in a new or unused portion of the rod. 55

Another object of the invention is to provide an improved form of equalizer rod in which the grooves vary in depth circumferentially of the rod but which have the same depth along any element of the surface 60 of the rod, whereby the rod may be turned or adjusted in position in the coating machinery either during operation thereof or when not in operation so as to attain any desired depth of coating on the paper or transfer 65 sheets.

Another object of the invention is to provide an equalizer rod of such a form that it may be readily heated or cooled during the 70 coating process so as to attain uniform results in the coating substantially independently of the surrounding temperatures. By providing an equalizer rod which may be heated, for example, the over-heating of the dope or coating material in the dope pan 75 may be entirely obviated.

A further object of the invention is to provide means for adjusting the equalizer rod in position in the coating machine so that it may be raised or lowered so as to 80 increase or decrease the angles at which the paper approaches or leaves the equalizer rod and whereby any desired contact pressure between the paper and the equalizer rod may be attained, thereby regulating the depth of 85 coating upon the paper or transfer sheets.

With these and other objects in view the invention comprises the following features hereinafter more fully described and particularly defined in the claims. 90

The various features of the invention are illustrated in the accompanying drawings showing a preferred embodiment of the invention and a modification thereof, in which— 95

Fig. 1 is a diagrammatic view of the essential parts of a coating machine showing the relative position of the equalizer rod therein;

Fig. 2 is a view of a portion of an equalizer 100

rod embodying the preferred form of my invention, the size of the grooves therein being exaggerated in order to more clearly show the construction and showing a bearing on one side of the rod in section;

Fig. 3 is a sectional view of the equalizer rod shown in Figure 2 taken on the line 3—3;

Fig. 4 is an end view partly in section of the equalizer rod bearing shown in Figure 2;

Fig. 5 is a view of the supporting means for the equalizer rod by which the rod may be adjusted in position in the coating machine to attain any desired set;

Fig. 6 is a detail view of a means by which jiggling or vibrating motion of the equalizer rod may be attained;

Fig. 7 is a view in elevation of a preferred form of dial employed for resetting or attaining any desired set of the equalizer rod; and

Fig. 8 is a view of a modified form of equalizer rod in which a helical form of groove is employed, the size of the groove being exaggerated in proportion to the size of the rod in order to clearly show the form thereof.

Referring more particularly to the drawings, 10 indicates a supply roll upon which a paper, which is to be coated, is mounted. The paper in passing through the coating machine passes first over a suitable guide or guides 12 which may be in the form of rollers, for example, and from thence over an edge or roller 14, then under a roller 16, then over a roller 18, preferably positioned above the roller 16, and from thence under a roller 20 into contact with a coating roller 22 or other suitable device by means of which the dope or coating material may be applied to the paper or sheet. The rollers 14, 20, may be pivoted upon an adjustable arm 21 mounted upon a standard 23, whereby the tension of the sheet or paper in passing through the rollers may be regulated. The roller 22 may be mounted in any desired manner in the machine so as to dip into a dope pan 24 containing the inking or coating material to be coated upon the paper. As the paper passes over the coating roller, the transfer pigment or inking material which is taken up from the dope pan by the roller, is gradually applied to the under surface of the paper. The coating material in the pan 24 is preferably heated so as to attain the desired consistency, by means of which the amount of dope taken up by the roller and applied to the paper is regulated to some extent. In general, a slight excess of the inking material is applied to the paper by means of the roller, which excess it is necessary to remove in order to attain a uniform thickness of the coating thereon. In order to remove the excess of coating, the paper is passed into contact with the equalizer rod 26 which serves to spread and to smooth out the inking material on the paper and also, apparently, to force it into more or less intimate contact with the superficial portions of

the paper and serves to remove the excess of coating material which may be made to return to the dope pan by any desired means such, for example, as an inclined plate extending from under the equalizer rod to the pan. As illustrated in Figure 1, the paper is preferably passed over the equalizer rod 26 but if desired the various parts could be reversed in such a manner that the paper will pass under the rod in order to remove the excessive coating which, in this case, would be applied to the top surface of the paper sheet. From the equalizer rod 26 the paper may be passed under a suitable cooling roller 28 or a series of such rollers if desired, and may be buffed or polished in the usual manner, after which it is wound upon a roller or reel 30 at the completion of the coating process.

The preferred form of equalizer rod comprising my invention consists of a cylindrical metal bar 32 having a series of depressions or grooves 34 therein disposed substantially in planes at right angles to the axis of the bar and preferably spaced equi-distantly along the bar. The grooves are preferably so disposed that the depth thereof varies circumferentially of the rod, but in such a manner that the groove depth along any element of the rod (parallel to the axis thereof) is the same. In other words, the depth of the grooves along any element of the rod is uniform so that whatever portion of the equalizer rod is employed in the coating process the depth of the coating produced by the rod on the paper will be uniform. I preferably form the grooves in the rod by employing a series of perforated discs or washers 36, 38, which are preferably mounted upon a hollow rod 40 and secured thereto by any suitable means such as a key 42. The washers may be securely fastened longitudinally of the rod by means of lock nuts 44 attached at the ends of the rod, and thus serving to hold the washers tightly together. I preferably employ two sizes of washers, the washers being so mounted that the alternate washers are of the same size and arranged concentrically. The larger washers are preferably mounted so as to be concentric with the axis of the equalizer rod or in other words, in such a manner that the axis of the equalizer rod passes through the centers of the washers 36. The smaller washers 38 are preferably mounted so as to be eccentric with respect to the larger washers and the axis of the rod but concentric with respect to each other, as above stated.

In the preferred form of my equalizer rod, I provide means for heating or cooling the rod so as to attain any desired temperature of the rod during the coating process. In order to accomplish this result I preferably pass the heating or cooling medium through the pipe or hollow rod 40. Any suitable medium, such as steam or water, may

be passed through the chamber or hollow portion of the hollow rod 40 by means of suitable pipe connections attached to the rod serving to conduct the temperature controlling medium to and exhaust it from the chamber. The connections between the pipes conducting the temperature controlling medium and the equalizer rod are preferably flexible in order to permit adjustment of the equalizer rod. Rubber hose connections may be employed, for example, of sufficient length to permit the desired movement of the rod. In place of the form of heating chamber shown in Figure 2, I might use hollow washers or washers having a part of the central portion removed so as to form a heating or cooling chamber in the washers when assembled in the manner indicated more particularly in Figure 5. I may obviously, employ any form of chamber, either of the form having a continuous wall through the washers or one in which a larger chamber is employed in the larger washers so as to attain substantially the same degree of heating and heat conductivity through both the larger and the smaller washers. In place of passing a heating medium through the chamber or chambers, as above set forth, I might employ an electrically operated heating unit as will be apparent to those skilled in the art.

The means which I preferably employ for supporting the equalizer rod in position in the coating machine comprises two supports 46, 48, which may be integral with the frame of the machine or adapted to be moved in any desired position by means of any suitable clamping or securing means 50, 52, as indicated in Figure 5. The supports are preferably made hollow, having cylindrical openings therein so as to be adapted to hold rods 54, 56, therein, suitable means being provided to hold the rods in any desired position. Any suitable means may be employed for adjustably holding the rods in the supports 46, 48, but I preferably employ racks 58, 60, and pinions 62, 64 for this purpose, the racks being formed along the length of the rods, as shown in Figure 5. The pinions 62, 64, may be either mounted on the same shaft or independently mounted, although I preferably mount them independently. The positions of the pinions may be adjusted by means of hand wheels 66, 68 connected to the pinions, the positions of the pinions and consequently the set of the equalizer rods being indicated by suitable means such as dial mechanisms 70, 72, the preferred form of dial being shown in detail in Figure 7. The pinions 62, 64 are mounted so as to pass through openings 74, 76 in the standards 46, 48, thereby contacting with the racks 58, 60 on the rods 54, 56 respectively. By means of the dials the equalizer rod may be adjusted in any desired position without preliminary trial sets. It is to be understood, however, that in place of the dials I might employ marks on the movable bearing rods 54, 56 in order to indicate the set of the equalizer rod and to attain the desired adjustment thereof.

The equalizer rod is preferably flexibly held in position so as to allow a certain amount of play or to compensate for irregularities in the paper passing over the equalizer rod which otherwise would vary the tension in the paper. The equalizer rod may be held in position by means of two suitable cylindrical supporting members 78, 80, which may be attached to the rods 54, 56 respectively, so as to permit relative movement of the cylindrical supporting members and the rods. The casings of the cylindrical members 78, 80 are preferably so mounted as to enclose the upper portions of the rods 54, 56, thereby permitting relative movement of the rods and the cylindrical members. Within the casings 78, 80, I preferably provide a series of springs 82 which are suitably attached to inner and outer bearing members 84, 86, such as by means of lugs 88, 90, for example. The equalizer rod is preferably attached to the inner member 84 by means of a key 92, but any other suitable means for attaching the equalizer rod thereto may be employed. The outer bearing member 86 is preferably secured in position within the casings 78, 80 by means of set screws 94 passing through the outer wall of the casing and serving to hold the equalizer rod in any desired position. After the equalizer rod has become worn in any particular position or along any element of the rod, the set screws 94 may be loosened and the equalizer rod turned to an unused position of the rod, giving any desired depth of coating, after which the set screws are again turned down, fastening and holding the equalizer rod in its new position.

It is to be understood that any suitable size of equalizer rod may be employed having any desired size of grooves therein and bearing members for holding the rod in position, and the exact proportions of the various parts have not been shown in the drawings, but the size and proportion of the various parts to be employed in any particular machine will be apparent to those skilled in the art.

It may be desirable, particularly with the smaller sizes of rods, to employ a supporting brace to keep the rod straight or the rod may be fitted with adjusting screws supported by means of a plate or brace so as to act against the rod and spring it into a slight arc in order to attain the desired effect in the coating of the paper. It is also desirable to employ means for indicating the angular position of the rod such as the indicator shown in the drawings (Fig. 5), whereby the rod may be set in any desired angular position.

In order to attain uniformity in the coating

and to prevent adherence of any foreign particles such as bits of fibre or lumps in the dope from adhering to the equalizer rod, I preferably employ means for causing a rapid movement of the equalizer rod back and forth across the sheet or, in other words, in a direction so that the rod moves longitudinally back and forth across the sheet. In order to attain this movement I preferably employ a cam 96 or a disc eccentrically mounted upon a shaft 98, which may be rotated by any suitable means such as a flexible connecting member 100 indicated in Figure 5. To the cam 96 is connected a lever 102 which is preferably pivoted or fulcrumed at a point 104 upon a suitable bracket 106, which may be connected to the casing 78 so as to be movable therewith when the equalizer rod is adjusted in position. An arm 108 of the lever 102 preferably extends upwardly so as to contact with or fit into a groove 110 formed on the projecting portion or bearing portion of the equalizer rod. The other arm 112 of the lever 102 is preferably forked so as to pass outside of the cam 96 which as it revolves, reciprocates the arm 112 of the lever 102 around the fulcrum 104 as a pivot and thereby causes reciprocation of the arm 108 of the lever and a corresponding backward and forward movement of the equalizer rod.

During the operation of the coating machine the equalizer rod may be reciprocated or not as may be found desirable, depending upon the consistency of the coating material or dope and the character of the paper to which it is applied, as will be evident to those skilled in the art.

In place of the equalizer rod formed in the manner as above described, I may employ a modified construction in which the grooves on the surface of the rod are formed in a helix, the axis of which is eccentric with respect to the axis of the rod, whereby the grooved depth along any element of the rod is the same but varies circumferentially of the rod as is attained in the preferred form of the invention as above described. The depressions or grooves in the preferred form of my device may be of any shape, either rectangular, parabolic, or may be in the form of an arc, or may be V-shaped in section, if desired. I prefer, however, the rectangular form of cross section which may be easily attained in either the preferred or modified form of the device.

In Figure 8 of the drawings, it will be understood that the depth and size of groove has been greatly exaggerated in order to clearly show the form thereof. I desire to have it understood, however, that I prefer not to be limited as to the size or shape of the groove, or the diameter or size of the equalizer rod and that various changes or modifications may be made in the invention as above described without departing from

the spirit or scope thereof. The corners or edges of the grooves may be rounded or beveled so as to eliminate edges on the rod which would tend to produce markings on the paper.

It is also to be understood that I may employ any material suitable for the purpose in making the equalizer rod, although I prefer to use a tough grade of steel, such as Swedish Bessemer steel, for example, which is preferably suitably tempered. Furthermore, the various rollers which revolve in the coating machine illustrated may be driven in any desired manner, either by means of a friction drive or by means of gears or in any other suitable manner. I preferably also provide means by which the speed of the various rollers may be varied and for this purpose I may independently run any or all of the rollers. The rollers 14 and 16 shown in the drawings are preferably maintained stationary in order to provide the desired tension in the paper at these points. By shifting the relative position of the rollers 14 and 16, as by changing the position of the roller 14, the tension in the paper at this point may be regulated. The tension in the paper may further be regulated by providing a suitable brake on the axle of the supply roller 10, or by providing means equivalent thereto. The apparatus may be employed for single or full carbons as will be apparent to those skilled in the art. Various changes may be made in the invention, as is obvious, without departing from the scope thereof as defined in the claims.

What I claim as new is—

1. In a coating machine an equalizer rod which comprises a rod having a series of depressions in the outer surface thereof, said depressions having a uniform depth in any given position along the length of said rod and a varying depth circumferentially of said rod, and means for mounting the said rod in a coating machine comprising flexible bearings whereby the operation of said rod will remain substantially uniform irrespective of inequalities in the paper or the dope applied thereto.

2. In a coating machine an equalizer rod which comprises a rod having a series of depressions in the outer surface thereof, said depressions having a uniform depth in any given position along the length of said rod and a varying depth circumferentially of said rod, means for mounting the said rod in a coating machine comprising flexible bearings whereby the operation of said rod will remain substantially uniform irrespective of inequalities in the paper or the dope applied thereto, and means for maintaining a backward and forward movement of said rod in a direction along the axis thereof.

3. In a coating machine an equalizer rod adapted for the spreading of dope in the

making of transfer sheets which comprises a substantially cylindrical rod, a series of grooves therein having a uniform depth in a given angular position of said rod but having a uniformly increasing or decreasing depth circumferentially of said rod, means for flexibly mounting said rod in a paper coating machine, and means for raising and lowering said rod to attain any desired elevation thereof in said machine.

4. In a coating machine an equalizer rod adapted for the spreading of dope in the making of transfer sheets which comprises a substantially cylindrical rod, a series of grooves therein having a uniform depth in a given angular position of said rod but having a uniformly increasing or decreasing depth circumferentially of said rod, means for flexibly mounting said rod in a paper coating machine, means for raising and lowering said rod to attain any desired elevation of said rod in said machine, means for vibrating said rod in a direction along the axis thereof, and means for indicating the angular position of said rod whereby said rod may be maintained in any desired angular position to attain the desired grooved depth in contact with the paper to be coated.

5. In a coating machine an equalizer rod adapted for the spreading of dope in the making of transfer sheets which comprises a substantially cylindrical rod, a series of grooves therein having a uniform depth in a given angular position of said rod but having a varying depth circumferentially of said rod, means for flexibly mounting said rod in a paper coating machine comprising adjustable spring mounted bearings, means for raising and lowering said rod to attain any desired elevation of said rod in said machine comprising standards adapted to be raised and lowered by means of racks and pinions connected therewith, means for indicating the elevation of said rod whereby the rod may be set in any desired position, means for indicating the angular position of said rod with respect to said paper, and means for producing a reciprocatory movement of said rod along the axis thereof whereby the coating material or dope will be evenly distributed upon the paper to be coated.

6. An equalizer rod comprising in combination a support extending axially of the rod, a plurality of sets of perforated discs of different diameters threaded on said support, the disks in each set being of the same thickness, the discs of different diameters being arranged in alternation on the support to form peripheral grooves in the rod, and means for clamping said discs together on said support.

7. An equalizer rod comprising in combination a support extending axially of the rod, perforated discs of different diameters threaded in alternation on said support so as

to form peripheral grooves in the rod, the discs of one of said sets being arranged eccentric to the axis of the rod, and means for clamping said discs together on said rod.

8. An equalizer rod comprising a pipe, a plurality of sets of perforated discs of different diameters threaded on said pipe, the disks in each set being of the same thickness, the discs of different diameters being arranged in alternation on the pipe to form peripheral grooves in the rod, and means for securing said discs on said pipe.

9. An equalizer bar having a series of spaced projections for engaging the web of paper or fabric, each projection having a face for engaging the paper or fabric which extends substantially parallel with the same in the direction of the length of the bar.

10. An equalizer bar having a series of spaced projections for engaging the web of paper or fabric, each projection having a face for engaging the paper or fabric which extends substantially parallel with the same in the direction of the length of the bar, and means for vibrating the bar longitudinally.

Signed at New York, New York, this 14th day of February, 1925.
